INDICATOR FOR SETTING STEAM ENGINE VALVES

Filed June 8, 1925

UNITED STATES PATENT OFFICE.

STANLEY B. MUSSelman, OF SARNIA, ONTARIO, CANADA.

INDICATOR FOR SETTING STEAM-ENGINE VALVES.

Application filed June 8, 1925. Serial No. 35,827.

My object in the present invention is to devise means for indicating the position of the valve relative to the ports at any given time and at any point in the stroke of the piston and also for obtaining a diagram recording the points in the piston stroke at which the valve events, pre-admission, cut-off, release, and closure occur and also the width of steam and exhaust port openings at any given position of the travel.

I attain my object by providing a drum rotatable to indicate the piston movement and by arranging a stylus for co-operation therewith adapted to be moved parallel to the axis of the drum to indicate valve travel. Means are also provided adapted to be set to show the positions of the ports with which co-operate pointers movable with the valve and adapted to be set to accord with the positions of the valve parts relative to one another.

The device is hereinafter more fully described and is illustrated in the accompanying drawings in which

Fig. 1 is a side elevation of the device shown in position on a locomotive engine;

Fig. 2 a plan view of the device partly in section;

Fig. 3 an end elevation of part of the same;

Fig. 4 a sectional detail showing a method of adjusting the indicator blocks;

Fig. 5 a specimen diagram showing the various lines marked thereon.

In the drawings like numerals of reference indicate corresponding parts in the different figures.

Referring particularly to Fig. 1, 1 is a cylinder of a locomotive engine and 2 the piston. Superimposed on the cylinder is the valve chest 3 in which the piston valve 4, of ordinary type, is slidable. One end only of the valve is shown, and the port 5 at one end of the cylinder. It will be understood of course, that the valve and ports may be of any ordinary construction as regards details not shown.

My device is provided with a frame 7 provided with a cross bar 8 adapted to be bolted to the end of the valve chest when the head of the latter is removed. A sliding rod 9 is slidable longitudinally of the frame, preferably in axial alignment with the valve. This rod is provided at one end with jaws 10 adapted to embrace the nut

usually found on the end of a valve. The jaws are provided with clamping screws 11 whereby they may be secured to the nut. The sliding rod thus moves synchronously with the valve.

On the frame 7 is journalled a drum 12. This may be of the type commonly employed in recording mechanism, and will be provided with the usual means, not shown, for securing a sheet of paper about its periphery. The drum is loose on the shaft 13, so that it may be rotated freely by hand when necessary.

Adjacent one end of the drum is provided a sleeve 14, on which is rotatably mounted a sleeve 15 provided with a knurled head 16 whereby it may be rotated. This sleeve is externally threaded to engage the threaded hub 17 of a pulley 18. The end of the drum and the pulley carry respectively the parts of a cone clutch 19. By screwing or unscrewing the sleeve 15 through the medium of its knurled head 16, the clutch may be engaged or disengaged as may be desired and the drum thus freed from or given a driven engagement with the pulley 18. Over the pulley 18 is led a belt 20 which is carried round suitable guide pulleys 21 and secured by one end to the end of the piston 2 or any suitable part moving synchronously with the piston. A weight 22 secured to the other end of the belt serves to keep it taut. From this construction it follows that the drum will be rotated in one direction or the other in accordance with the movements of the piston.

The sliding rod 9 serves as a stylus carrier, one or more styli being secured thereto. Each stylus comprises a spring-pressed member adapted to engage the surface of the drum, which member is retractable in known manner. The sliding member is carried in a split clamp 23 which may be adjusted longitudinally of the sliding rod. Usually two styli will be employed, one for use when the engine is operating in a forward direction and the other for use when the engine is in reverse. From this construction it is evident that a diagram may be produced on the drum which represents the compounding of the movements of the piston and the valve.

To give a visual indication of the positions of the ports and valves, I provide the following means. The frame 7 is provided

with guide slots 24 in which are movable indicator blocks 25 which serve as port edge markers. The slots are rabbeted as shown and the indicator blocks correspondingly rabbeted so that their upper surfaces are flush with the upper surface of the frame. Each block is provided with a threaded stem in which is screwed a nut 26. The blocks may thus be moved longitudinally of the slot and clamped in any desired position. The sliding rod 9 is also provided with pointers 27, each pointer being formed on a clamp 28 so that the pointers may be adjusted longitudinally of the sliding rod.

15. The device is used as follows. The device having been positioned and the sliding rod connected with the end of the valve, the port edge markers 25 are set by measurement to the positions of the edges of the ports with which the valve cooperates as to the width of the ports but the distance between the pairs of port edge markers may for convenience be less than the distance between the ports. The valve is then moved 20 to a position exactly central between the two ports and by measurement the pointers 27 are then set to bear the same relation to the port edge markers that the edges of the parts 29 of the valve bear to the edges of the ports. When the engine is turned over, the exact travel of the valve relative to the ports can be seen and rough adjustments in the setting of the valve gear readily made.

30. A diagram is necessary to enable the necessary final adjustments to be made and this diagram is secured in the following manner. The drum is freed from its driving connections in the manner hereinbefore described. The stylus, when the valve is 35 in the central position, hereinbefore referred to, is suitably located at about the centre of a sheet of paper positioned on the drum and clamped in position on the rod 9 so that its relation to the valve becomes a fixed quantity. The drum is then rotated by hand 40 so that the stylus will score a line *a* (shown in Fig. 5) on the paper, which will, of course, be straight when the diagram is removed from the drum.

45. In a similar manner a line *b* is drawn at each side of the centre line first drawn and separated from it by an amount equal to the steam lap or steam clearance represented by *a*—*b* in Fig. 5. This is done by sliding 50 the rod 9 until the pointer 27 which represents the outer or admission edge of the ring 29 is lined up with the port edge marker which marks the outer or admission edge of the port it cooperates with. The drum is 55 then rotated as before, the stylus marking a straight line *b* thereon.

The admission edge pointer on each side is then moved to line up with the corresponding exhaust edge marker, and another 60 line *c* is drawn in each side parallel to the

last and separated by the width of the ports, the width of the ports being represented by *b*—*c* in Fig. 5.

Often a valve has either exhaust lap or exhaust clearance. To mark this lap or clearance the pointers representing the inner or exhaust side of the ring 29 are lined up with the corresponding marker which marks the inner or exhaust side of the ports. If a valve is line-on-line on the exhaust edges, the centre line will record the release and closures and exhaust lines are not required.

75 These parallel lines drawn as described form the basis of the diagram. The stylus can then be retracted as provided for and the engine turned over on the rollers provided in the shops for this operation.

These parallel lines drawn as described form the basis of the diagram. The stylus can then be retracted as provided for and the engine turned over on the rollers provided in the shops for this operation.

80 The exact travel of the valve relative to the ports can be seen by observing the port edge markers and pointers and rough 85 adjustments of the valve gear can be made to correct the errors.

85 Next place the piston at either extreme of its stroke and then engage the drum by 90 means of the clutch to the driving pulley. Then allow the stylus to engage with the paper at the end of the latter corresponding with the piston position.

95 The valve at this time should be displaced from its central position an amount equal to one steam lap plus one lead and so the stylus will rest on the paper at point *d*, Fig. 5, a short distance, $\frac{1}{4}''$, $\frac{1}{8}''$, or so, beyond the lap line *b* in the space on the paper representing the port.

100 Turning the engine over now results in the compounding of the valve and piston movements producing a curve which records the actual position of the valve relative to the ports at any point of the piston stroke and return.

105 Wherever the curved line intersects the straight parallel lines indicates that an edge of the valve has registered with an edge of the ports.

110 The diagram, which is elliptical when removed from the drum, can be placed on a drawing table and trimmed up and utilized to yield the information it contains.

115 The length of the ellipse measured at right angles to the centre line represents piston travel. The width of the ellipse measured parallel to the centre line represents valve travel.

120 In this manner the exact piston position, when the valve events pre-admission, cut-off, release and closure, occur, are recorded and can quickly be tabulated into a complete valve report.

125 The duration of cylinder events, such as pre-admission, admission, expansion, exhaust, and compression can also be observed.

130 From the information thus obtained the necessary deductions may be made to enable the valve gear to be properly set and

the finer adjustments made which are so essential to obtain a nicely balanced, smooth working engine.

What I claim is:

- 5 1. In an indicator for setting steam engine valves, the combination of a frame adapted for connection at the front end of the valve chest of a locomotive; a rotary drum mounted on said frame; means for rotating 50 the drum in synchronism with the movements of the piston of the engine; a stylus carrier slidable on the frame; means for directly connecting the stylus carrier with the end of the valve in the valve chest for 55 positive movement in either direction; and a stylus connected to the carrier adapted to co-operate with the drum.

2. In an indicator for setting steam engine valves, the combination of a frame adapted 20 for connection at the front end of the valve chest of a locomotive; a rotary drum mounted on said frame; means for rotating the drum in synchronism with the movements of the piston of the engine; a stylus 25 carrier slidable on the frame; means for directly connecting the stylus carrier with the end of the valve in the valve chest for positive movement in either direction; and a stylus adjustable lengthwise of the carrier 30 and adapted to co-operate with the drum.

3. In an indicator for setting steam engine valves, the combination of a frame adapted 25 for connection at the end of the valve chest of a locomotive; indicator members adjustable longitudinally of the frame to indicate port openings and positions; a rod slidable longitudinally of the frame; means for connecting the rod with the end of the valve 35 in the valve chest; pointers adjustable longitudinally of the rod adapted to be set to accord with the positions of the valve parts and to co-operate with the port indicator to show the positions of the valves and ports 40 at any point of the stroke of the valve; a 45 drum rotatably mounted on the frame;

means for rotating the drum in synchronism with the movements of the piston of the engine; means for freeing the drum at will; and a stylus carried by the sliding rod aforesaid adapted to co-operate with the drum, 50 the said port indicators and pointers serving to enable the stylus to be set to scribe datum lines on a sheet carried by the drum aforesaid when the latter is free, the stylus being adapted to scribe a curve on the sheet 55 compounding the movements of the valve and piston rod when the drum is rotated in synchronism with the movements of the said rod.

4. In an indicator for setting steam engine valves, the combination of a frame; indicator members adjustable longitudinally of the frame to indicate port openings and positions; a rod slidable longitudinally of the frame; means for operating said rod in 60 synchronism with a valve; pointers adjustable longitudinally of the rod adapted to be set to accord with the positions of the valve parts and to co-operate with the port indicators to show the positions of the valve 65 and ports at any point of the stroke of the valve; a drum rotatably mounted on the frame; means for rotating the drum in synchronism with the movements of the piston of the engine; means for freeing the 70 drum at will; and a stylus carried by the sliding rod aforesaid adapted to co-operate with the drum, the said port indicators and pointers serving to enable the stylus to be set to scribe datum lines on a sheet carried 75 by the drum aforesaid when the latter is free, the stylus being adapted to scribe a curve on the sheet compounding the movements of the valve and piston rod when the drum is rotated in synchronism with the 80 movements of the said rod.

Signed at Sarnia, Canada, this 21st day of May, 1925.
